UNITED STATES PATENT OFFICE

WILLIAM C. SCHMIDT, OF OAK PARK, ILLINOIS, ASSIGNOR, BY MESNE ASSIGNMENTS, TO T. W. & C. B. SHERIDAN COMPANY, OF NEW YORK, N. Y., A CORPORATION OF NEW YORK

HEADBANDING APPARATUS

Application filed July 18, 1927. Serial No. 206,723.

This invention relates to headbanding apparatus, useful in the book binding art, and more particularly has reference to an apparatus for forming and affixing headbands to book linings and/or to books.

It is generally customary in the art of high grade book binding to follow the steps of first rounding the book and stitching the signatures together. A super composed of crash or some other suitable fabric or fibrous material is then applied to the back, and headbands are affixed to the top and bottom. A back lining of paper is then applied overlapping the headbands and covering the super, and a cover or case is subsequently attached to the back.

An object of this invention is to provide an apparatus for applying headbands to books.

Yet another object of this invention is to provide an apparatus for applying headbands with back lining attached to books.

Still another object of this invention is to provide an apparatus for forming headbands for books, also forming headbands and attaching them to back lining material.

A further object of this invention is to provide an apparatus for forming headbands and applying the headbands with back lining attached to books.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a side elevational view of the

apparatus for forming and applying headbands to back linings and books;

Fig. 2 is an enlarged vertical transverse sectional view showing the feeding, severing and applying mechanism;

Fig. 3 is a vertical cross sectional view partly broken away, taken on line 3—3 of Fig. 2;

Fig. 4 is a vertical transverse sectional view showing the headband forming mechanism;

Fig. 5 is a horizontal sectional view taken on line 5—5 of Fig. 4;

Fig. 6 is a horizontal sectional view taken on line 6—6 of Fig. 2;

Fig. 7 is a detail sectional view of the one way drive taken on line 7—7 of Fig. 8;

Fig. 8 is a sectional view taken on line 8—8 of Fig. 7;

Fig. 9 is a top plan view of the forming or folding device or chute;

Fig. 10 is an end elevation of the forming chute.

Referring first to Figure 1, there is shown the complete apparatus for forming headbands and applying the headbands to back linings and to books. The apparatus comprises a base surmounted by oppositely disposed supporting standards 1, shown partly broken away, having extended horizontal top sections 2 formed integral therewith. A frame 3 is seated in an indentation formed in the horizontal top section 2. Brackets 4 are mounted on the extension 2 formed on the supporting standards 1 by bolts 5.

The frame 3 is formed of oppositely disposed sections having integral bushings designed to receive a shaft 6. A driving gear 7, having a silent ratchet 8 formed integral therewith, as shown in Figure 7, is keyed to the shaft 6 by a spline 9. A pinion 10 is loosely mounted on the shaft 6, formed with a cap 11 adapted to fit over the ratchet 8 and be seated against the face of the driving gear 7.

A plurality of wedging rollers 12 are seated in notches having tapered seats in the face of the ratchet 8. The rollers 12 are provided with pushers 13 seated in apertures in the walls of the notches and held by spiral springs 14.

The cap 11 formed on the pinion 10 presses against the rollers 12 when rotated clockwise and advances the ratchet 8 and the driving gear 7. When rotated counter clockwise the rollers 12 are released and the cap operated without movement of the ratchet.

A roller 14, as shown in Figure 6 is mounted on the shaft 6 adapted to rotate with the ratchet 8. A housing cap 15 is fixedly mounted over the pinion 10 and is formed with an integral communicating channel guide casing 16 on one side to receive a rack 17, adapted to operate the pinion 10 independently of the shaft 6 and the ratchet 8.

The rack 17, as shown in Fig. 1, is extended to form a connecting rod 18 having a terminal collared bushing 19. A pin 21 is seated in the bushing 19 and is operable in a slot 22 formed in one end of an operating lever 23. The other end of the operating lever 23 is mounted on a shaft 25. A bell crank lever 26 formed with the collared bushing 24 is also mounted on the shaft 25.

A pin 28 is seated in an apertured extension 27 formed on one side of the operating lever 23, and acts as a fulcrum for a coupling latch 29. One end of the coupling latch 29 engages the heel of the bell crank lever 26, and the other end is held by a shaft 31 seated in one end of a trip lever 32, mounted on the frame 1 by a pin 33.

The coupling latch 29 is held in engagement with the trip lever 32 by a tension spring 34 having one end secured in an aperture 35 in the lever 23, and the other end attached to a lug 36 seated in the top of the coupling latch 29. The bell crank lever 26 is provided with an aperture 37 designed to receive a tension spring 38, to retain the lever against a suitable operating mechanism not shown.

One end of a rod 39 is attached to the trip lever 32 by a pin 31, and the rod is pivoted at its other end to an oscillating disk 41. One end of a link 42 is attached to the disk 41 and the other end pivoted to the arm 43 of a trip lever, its other arm 44 being adapted to engage a back roller 45 constituting part of a book clamp 47 traveling along the track 46.

If the machine is operated without a book in the clamp 47, the clamp will close and move leftward the roller 45, causing the roller to push the trip arm 44 back, and move the link 42 out and the trip rod 39 up. The upward movement of the trip rod 39 will lift the coupling latch 29 and disengage the mechanism from the heel of the bell crank lever 26. This disconnects the operating lever 23 and the operation of the ratchet 17 is prevented.

The rack 17, operating the pinion 10, intermittently advances the feed roller 14, retraction being prevented by the ball ratchet. A gear 48 is mounted on a shaft 49 journaled in the frame 3. The intermediate gear 51 is en-

gaged with a slitter operating gear 53 affixed to a shaft 54 mounted for rotative movement in the frame 3, and engages an adjacent slitter operating gear 55, mounted on a shaft 56 in a similar manner.

The slitter gear 53 meshes with an intermediate gear 57 carried by a shaft 58 and engaging a glue roller operating gear 59, mounted on a shaft 61. The teeth on the gear 59 mesh with teeth on a glue transfer roller 75 operating gear 62 keyed on a shaft 63.

The feed roller 14, operated by the ratchet 8 and the pinion 10, is adapted to engage a roller 64, as shown in Fig. 2. The roller 64 is mounted on the shaft 49 and operated by the gear 48. The gear 48 engaging the intermediate gear 51 mounted on the shaft 52 operates the gear 53, mounted on the shaft 54 and a slitter roller 65 also mounted on the shaft 54. The gear 53, operating the gear 85 55, operates an adjacent slitter roller 66, mounted on the shaft 56. The gear 53 on the slitter roller shaft 54 engaging the intermediate gear 57 mounted on the shaft 58, meshes with the gear 59 mounted on the shaft 61. There is also mounted on the shaft 61 a roller 67. The gear 59 operating the roller 67 engages the gear 62 mounted on the shaft 63. The roller 68 is keyed on the shaft 63 adjacent the roller 67 mounted on the shaft 61.

The frame 3, as shown in Figures 1 and 2, is formed with an integral seat 69 having seated thereon a pan 71. A bracket 70 having an integral bushing 72 adapted to receive a shaft 73 is mounted on the pan 71. A plurality of scrapers 74 are fixed on the shaft 73 by collars 75 having integral supporting arms 76 formed therewith, as shown in Figs. 2 and 6. The collars are positioned on the shaft 73 by set screws 77. The scrapers 74 contact with the rollers 68. These rollers are provided with integral collars 78 mounted on the shaft 63 and positioned by set screws 79.

The shaft 61 is journaled in the bracket 70, which is also provided with split bearings 83 and 84 on each end secured to the middle of the bracket by bolts 82. The bearings 83 and 84 act as bushings for the shaft 63 and the shaft 73.

The shaft 6 supporting the feed roller 14 is journaled in the frame 3 and held by a split bearing cover 85 held by bolts 86.

A plurality of collars 87 are mounted on the shafts 54 and 56 and held thereon by set screws 88, as shown in Fig. 3. The collars 87 are provided with annular faces 89 having peripheral knife edges 91. The faces are secured on the collars by screws 92. The adjacent peripheral knife edges 91 are aligned to act as slitters for the back lining web, and the positioning of the collars on the shaft determine the reduced width to which the web is trimmed to suit the book to be lined.

The extension 2 on the frame 1, as shown

in Fig. 1, is provided with a groove 93 adapted to receive an axle 94 supporting a spool 95. On the spool is wound the web or material for the back lining such as paper 96. The paper is introduced into the feeding mechanism over a roller 97 mounted on a shaft 98. The shaft 98 is journaled in integral collars 99 formed in the frame 3. The material is then threaded through the slitter shafts 54 and 56 and between the peripheral knife edges 91 so that it may be trimmed to any desired width. It then passes back around the roller 64 and up over the feed roller 14, and thence on to a feed table 101 formed integral with the frame 3.

The material is held on the feed roller by tractor pulleys 102, mounted on an axle 103. The axle 103 is seated in one end of arms 104 having an axle 105 seated in collared bushings 106 formed on the other end. The axle 105 is mounted in bearings formed on the frame 3. The set screws 107 are fixed in the collars 106 to position the arms 104 on the shaft 105.

For severing successive sections of back lining with headband attached a knife blade 108 is mounted on the frame 3 above the feed table 101. The knife blade is provided with a pressure line 109 communicating with nozzles 111 formed in the blade. The pressure line is fed from a flexible conduit 112 fixed to the line 109 by a collar 113 leading from any suitable source of pressure.

A lever 114 is keyed on the shaft 25, as shown in Fig. 1 and pivoted at the other end to a link 115 through a pin 115'. The link 115 is pivoted to a knife table 116 by a pin 117. The knife table 116 is adapted to reciprocate in a channel 118 formed in the frame 3 and in alignment with the path of the book clamp 47. On the top of the knife table 116 is mounted a backing table 119, preferably flexibly constructed, adapted to receive the material 96 fed under the knife blade 108.

The bell crank lever 26 oscillates the shaft 25, and jointly operates the lever 114 and the lever 23, reciprocating the knife table 116 and oscillating the pinion 10, thus alternately advancing the material under the knife blade 108 and reciprocating the knife table 116 and cutting the material 96 at the point of discharge under the knife blade. The material awaiting discharge is held on the feeding table 101 by air pressure through the conduit 109 and nozzles 111. The knife 108 is secured on the frame 3 by a stanchion 121 secured thereto by bolts 122. A link 123 is mounted in the end thereof, having the other end affixed in the knife 108 and adjusted by lock nuts 124 and 125 to adjust the position of the knife.

The frame 3 is formed with an integral bushing 126 adapted to receive a shaft 127 having mounted thereon a head band guide roller 128, as shown in Figure 2. There is

also formed on the frame 3 an integral bushing 129 designed to receive an axle 131 having mounted thereon a head band guide roller 132 adapted to cooperate with the feed roller 14. Headband strips 133 are introduced in the feed mechanism over the guide roller 128 and supplied with adhesive by contact with the glue transfer roller 68. They then pass over the guide roller 132 and are applied to the edges of the back lining 96 by contact with the feed roller 14 carrying the back lining.

A headband forming mechanism is mounted on each carrier bracket 4 secured to the extension 2, each adapted to refold tape material progressively into a headband strip and insert a cord in the fold to form a bead. The bracket 4 is provided on the upper end with a plurality of integral seats 134, having seated therein pins 135. A plurality of supporting disks 136 are mounted on the pins and are designed to act as seats for spools of cord 137. There are also formed on the bracket 4 a plurality of integral seats 138 adapted to receive angle rods 139, having eyelets 141 formed on their end. Collars 142 are secured on the rods 135 having casings adapted to receive guide rods 143.

The cords 137 are threaded through the eyelets 141, and carried over the guide rods 143 to rollers 144 mounted on a shaft 145. The shaft 145 is seated in bushings 146, formed integral with the brackets 4.

Extensions 147 are formed integral with brackets 4 or attached thereto having provided on their ends integral bushings 148, adapted to receive a shaft 149. The shaft 149 supports a reel 151 on which is wound tape material 152.

The tape passes over a roller 153 mounted in bushings 154 formed integral with the brackets 4 and a roller 155 mounted in bushings 156, also formed integral with the brackets 4. The tape is then threaded over a roller 157 mounted on a shaft 158 seated in integral bushings 159. The roller 157 depends into a pan 161, mounted on a frame 162, secured to the brackets 4. The tape then passes over a roller 163 mounted on a shaft 164, journaled in integral bushings 165, formed on the brackets 4.

The cords on the rollers 144 are designed to pass over the rollers 163 and be superimposed on the tape 152, also on the rollers 163 having adhesive faces applied by the roller 157. The tape and cords pass from the rollers 163 to forming devices or chutes 166, mounted on shafts 167, journaled in bushings 168 formed integral with the brackets 4.

Each forming chute 166, as shown in Figs. 9 and 10, is formed with flanged guide walls 169 and a pin 171 is attached by a bolt 172 adjacent the center. An additional pin 173 is mounted on the other side of the chute by a bolt 174. A pin 173 is provided with an arm 175 having formed on the end a hollow

cap 176, in which is seated a spiral spring 177, projecting against one side wall 169. The cap 176 adjacent to the center of the chute presses against the pin 171 by the action of the spring 177. The tape 152 passes over the roller 163 with the cord 137, and is folded over the cord in passing between the pin 171 and the cap 176, to form headbands 133 entering the backing apparatus 10 over the roller 128.

The operation of this invention may be as follows. The back lining web 96 on the supply spool 95 is introduced on the roller 98 and passed between the slitter shafts 54 and 56 as shown in Figs. 2 and 3. The plates 89 having peripheral knife edges may be adjusted longitudinally on the shaft to trim the paper web to any desired reduced width, or paper of the correct width to suit the books may be introduced, and the knife dispensed with. The paper is then passed over the roller 64 and back over the feed roller 14. It is deemed desirable to form the roller with a knurled surface to afford a firmer grip on the stock.

One face of the headband supply tapes 152 on the reels 151 may be previously treated to carry a suitable dry adhesive substance. The gummed surfaces are moistened and rendered adhesive by passage over the rollers 157, depending in the pan 161, filled with water or any other desirable moistener. If so desired ungummed supply tapes may be employed and the pan 161 filled with an adhesive substance applied directly to the tapes by the rollers 157.

The untreated faces of the tapes are then passed over the rollers 163. The cords 137 on the spools 135 are threaded through the eyelets 141 on the end of the angle rods 139, over the angle guides 143 and over the rollers 144.

The cords are progressively superimposed on the adhesive faces of the tapes on the rollers 163 and the tape and cords passed down in the forming or folding devices or chutes 166. The tape is folded over the cord by being passed between the pin 171 and cap 176, as shown in Figs. 8 and 9, the tape thus progressively formed into headband strip and the cord forming the bead.

The headbands 133 are advanced over the rollers 128 and over the rollers 62. The rollers 62 contact with the rollers 59, depended in the pan 71, filled with glue or any other suitable adhesive. The glue is transferred from the rollers 59 to the rollers 62 and an even film on the rollers maintained by the scrapers 74 as shown in Fig. 6, this film being applied upon one exposed side of the headband strip.

The headbands are then passed over the rollers 132 and thereby applied upon the edges of the paper web on the roller 14, from which the assembled web and headbands pass

under the knife blade 108. The paper with the headbands attached is held on the feed roller 14 by the tractor pulleys 102 and on the feed table 121 by air pressure introduced through the line 109 and down the conduits 111, as shown in Fig. 2.

A section of the lining is severed upon the table 119 by the rise of the applier carriage 116 and each severed headbanded lining section is applied to the back of the book, which has previously had a layer of wet adhesive applied to it.

If no book is in the clamp 47, the trip lever 44 operating through the parts 42 and 41 will lift the latch 32 and disengage the lever 23 from the operating bell crank 26 and so prevent the feeding of the lining to the empty clamp.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention.

I claim:

1. A back lining and headbanding machine for a book binding apparatus comprising means to form headbands, means to attach the headbands to back linings and means to attach to books the back linings with headbands affixed.

2. A back lining and headbanding mechanism for a book binding apparatus comprising means to form headbands, means to attach the headbands to back linings, and means intermittently to discharge portions of the back linings with the headbands attached.

3. A back lining mechanism for a book binding apparatus comprising means to form headbands, and means cooperating with the headband forming means to attach the headbands to back linings and means to attach to books the back linings with headbands affixed.

4. A back lining mechanism for a book binding apparatus comprising means to form headbands, means cooperating with the headband forming means to attach the headbands to back linings, and means to sever and discharge portions of the back linings.

5. An apparatus for forming headbands comprising means to supply tape material, having an adhesive face, means for moistening the adhesive face of said material, means to introduce a cord, means to fold the material over the cord, and means to apply adhesive to one face of the formed headband.

6. An apparatus for attaching headbands to back linings comprising means to supply the headband, means to apply adhesive to one exposed side of the head band, means to supply the back lining, means to trim the

back lining to a reduced width, means to attach the headband to the back lining, and means to discharge the back lining with headband.

5 7. An apparatus for attaching headbands to back linings comprising an attaching means, means to supply headbands and to apply adhesive to the headbands, the same operated by the attaching means, means to supply back lining and means to trim the back lining, the same operatively connected with the attaching means, and means including the attaching means to discharge the back lining with the headband attached.

10 15. 8. A back lining mechanism for a book binding apparatus comprising means to supply tape material, means for rendering adhesive the face of said material, and means to fold the material on the adhesive face, to form a headband, and means to attach the headband to back lining, including means to apply adhesive to one of them.

15 20 25 9. A back lining mechanism for a book binding apparatus comprising means to supply tape material, means to supply cord, and means to fold the tape material over the cord, to form headbands, means to attach the headbands to back lining, including means to supply the headbands, means to apply adhesive to the surface of the headbands, means to trim the back lining, means to attach the headbands to the back lining, and means to discharge the back lining with the headbands attached.

30 35 40 45 10. A backing mechanism for a book binding apparatus comprising means to supply tape material having an adhesive face, means to supply cord upon the material, and means to fold the adhesive face of the material over the cord, to form headbands, means to attach the headbands to back linings including an attaching means, means to feed the headbands, and means to apply adhesive to the headbands operated by the attaching means, and means to supply and trim the backlining operated by the attaching means.

50 55 11. A back lining mechanism for a book binding apparatus comprising rollers for conveying tape material and cord, a device for progressively forming headbands of the material and cord, means for supplying back lining, rollers for attaching the headbands to the back lining, and means to attach to a book back the linings with headbands affixed.

60 55 12. A back lining and headbanding machine for a book binding apparatus comprising means to form headbands, means to attach the headbands to back lining, and means to discharge the back lining with headbands attached.

65 13. A back lining mechanism for a book binding apparatus comprising means to form headbands, means cooperating with the headband forming means to attach the headbands to back lining and intermittently to discharge

a portion of the back lining with headbands attached.

14. An apparatus for attaching headbands to back linings comprising attaching means, means to supply headband strip, means to apply adhesive to one exposed side of the headband strip, means to supply back lining web, means to attach the headband strip to the web, and means to sever the back lining web with headband strip attached. 75

15. A back lining mechanism comprising means for supplying headband forming material and cord, devices for forming the material and cord into headbands, and rollers for guiding back lining web and for attaching the headbands to the back lining web and for discharging the back lining with the headbands attached. 80

16. A back lining mechanism comprising means for supplying headband forming material and cord, a device for forming headbands of the material and cord, rollers for guiding back lining and for attaching the headbands to the back lining, and means cooperative with the rollers to intermittently discharge part of the back lining with the headbands attached. 85

17. In a book binding machine having a holder for a book, means for supporting a supply of back lining web, severing means for cutting off predetermined portions of such web and means for guidingly applying such severed portions to the back of a book, in combination with means for supporting a supply of headband tape, means for folding 100 said tape upon itself to form a headband strip, and means for adhesively applying said strip to back lining web taken from said supply. 95

18. For use with a book binding machine, means for supporting a supply of back lining, means for holding a supply of tape material for forming a headband, means for holding a supply of twine, means for centering such twine longitudinally of said tape 110 and for folding said tape over such twine to form headband strip, and means for uniting said back lining and headband strip with twine to provide a continuous band. 105

19. An instrumentality to be used with a book binding machine comprising a holder for a supply of sheet material, a holder for a supply of headband material, a holder for twine, and means for folding said headband material, inserting twine therein, and uniting the folded headband to the sheet material. 115 120

20. A back lining mechanism for book binding apparatus comprising means for supporting headband tape having an adhesive face, a support for twine, means for moistening the adhesive face, folding the tape and inserting the twine in the fold, to form headband strip, means to supply a web of back lining material, means to trim said 125 130

- web to reduce its width, means to attach the formed headband strip to back lining material to form a composite web, means to discharge the web of back lining material with headbands attached, and means for severing successive portions of the composite web.
21. In a book binding machine having means for positioning successive books, the combination of means for progressively forming a tape into a headband strip, means for feeding the strip and for severing successive headbands therefrom, and means for applying each severed headband to a book.
22. A machine as in claim 21 and wherein the forming means comprises means for folding the tape upon itself, means for inserting a cord in the fold to form a bead at one edge of the strip, and means for rendering the tape adhesive to fix it in folded condition.
23. In a book binding machine having means for positioning successive books, the combination of means for progressively forming a tape into a headband strip, means for feeding a back lining web and progressively applying the headband strip thereto, means for severing successive sections from the united web and strip, and means for applying each section to a book.
24. A machine as in claim 23 and wherein is means operating by reason of the absence of a book for preventing the feeding and severing of sections of headbanded back lining.
25. A book headbanding and back lining machine having means for holding successive books with glued backs exposed, the combination of means for feeding a back lining web, means for forming tape material into a headband strip and applying it progressively to one or both edges of the web, means for rendering one of said components adhesive to secure them together, means for severing from the advancing web a headbanded back lining, and means for applying the same to the glued back of each book.
26. In a machine of the class referred to, the combination of mechanism for advancingly feeding a back lining web, means supplying tape material, means for folding such material progressively upon itself, and means supplying cord into the fold, thereby forming a headband strip, means rendering one of said components adhesive, and means progressively applying the headband strip to the advancing back lining web.
27. In combination, a device to form tape material progressively into headband strip and means for feeding a back lining web and progressively affixing the headband strip thereto to produce a continuous web of headbanded back lining web.
28. In combination, a device to form tape material progressively into headband strip and means for feeding a back lining web
- and progressively affixing the headband strip thereto to produce a continuous web of headbanded back lining web, and means for transversely severing successive sections thereof to produce individual headbanded back lin- 70
- ings.
29. In combination, means for progressively feeding a back lining web, means to trim it to a predetermined reduced width during feed, and means to affix progressively 75 to each edge of the reduced web, a headband strip.
30. A mechanism for progressively forming headband strip comprising a roll over which tape material travels, means supplying cord to the exposed side of the tape on the roll, a device beyond the roll for progressively folding the tape upon itself after passing from the roll, with the cord at the fold forming a bead in the produced strip, and means for rendering adhesive the surface of the tape before reaching the folding device. 80
31. A mechanism as in claim 30 and wherein the roll has a face groove into which the cord may depress the tape. 90
32. A mechanism as in claim 30 and wherein beyond the folding device are rolling means progressively pulling the folded and unfolded material through the cord applying and folding points. 95
33. A mechanism as in claim 30 and wherein the folding device consists of a base or plate and pressure members outstanding therefrom, recessed to accommodate the bead in the strip produced by the interior cord. 100
